United States Patent Office.

T. C. RICE, OF WORCESTER, MASSACHUSETTS.

Letters Patent No. 79,258, dated June 23, 1868; antedated June 9, 1868.

IMPROVEMENT IN TUBULAR AXLE.

The Schedule referred to in these Letters Patent and making part of the same.

TO ALL WHOM IT MAY CONCERN:

Be it known that I, T. C. Rice, of Worcester, in the county of Worcester, and State of Massachusetts, have invented a new and improved Tubular Wagon-Axle; and I do hereby declare that the following is a full, clear, and exact description thereof, which will enable those skilled in the art to make and use the same, reference being had to the accompanying drawings, forming part of this specification.

Figure 1 represents one end of my improved tubular axle.

Figure 2 is a cross-section, taken in the line x x , fig. 1.

Figure 3 is a cross-section, taken in the line y y , fig. 1.

Figure 4 is a longitudinal section of the arm, showing how it is inserted in the tube of the body of the axle. Similar letters of reference indicate corresponding parts.

This invention relates to improvements in the construction of tubular axles for wagons and other vehicles; and they consist, first, in attaching shouldered offsets on the axle, over which to fasten the clips to hold the tube fast in place on the wooden bed of the axle; and, secondly, in inserting smaller tubes in the ends of the main tube or body or barrel of the axle, for the arms, which extend into the tube beyond the collar, to give requisite strength, as hereinafter fully described.

A represents the body of the axle, formed of iron gas-pipe or other suitable metal pipe.

The tube A is let into the bed B, and is secured to it, as axles are usually secured, by clips a a ; but in order to make them fast together, and prevent loosening and slipping of the barrel of the axle, I braze or otherwise attach square-shouldered offsets c c to the axle, upon which offsets the clips are bolted, as shown in the drawings.

In order to form the arm C smaller and with proper taper, without weakening it, and also to increase the strength of the axle at and near the inner end of the arm, I insert smaller tubes of metal in the ends of the tubular axle, and extending into it beyond or inside of the collar d , and upon the outer tube, or upon both tubes, outside of the collar, I taper or shape the arm.

The smaller tube, to form the arm, is inserted in the tubular axle as far as necessary to give the requisite strength to the connected parts, as shown in fig. 4, which parts may be united by brazing, screwing, shrinking together with recesses, or in any suitable manner to hold them fast together.

Having thus described my invention, I claim as new, and desire to secure by Letters Patent—

The square-shouldered offsets c c , on the axle A, for securing it to the wooden bed B, with the clips a a , which fit over such shoulder, as herein shown and described.
